United States Patent Office

Des. 189,049
Patented Oct. 18, 1960

189,049

GRAPPLE

Maurice M. McElderry, 8716 Arbor St., Duluth, Minn.

Filed Oct. 23, 1959, Ser. No. 58,041

Term of patent 14 years

(Cl. D41—1)

FIG. 1.

FIG. 2.

FIG. 4.

FIG. 3.

Figure 1 is a perspective view of a grapple embodying my new design, the tines being in an open position;

Figure 4 is a perspective view thereof, the tines being in a closed position.

I claim:

The ornamental design for a grapple, as shown.
